Specification for Design.

Patented July 11, 1922.

Application filed March 23, 1922. Serial No. 1,354. Term of patent 3½ years.

To all whom it may concern:

Be it known that I, ALBINA CABALKA, a citizen of the United States, residing at Geddes, in the county of Charles Mix and State of South Dakota, have invented a new, original, and ornamental Design for Dress Fabrics, of which the following is a specification, reference being had to the accompanying drawing, forming a part thereof.

The figure is a plan view of a dress fabric showing my new design.

What I claim is:

The ornamental design for a dress fabric, as shown.

Miss ALBINA CABALKA.
